APPARATUS FOR DRYING CLOTHES, LAUNDRY, ETC.

Filed Feb. 24, 1930

Inventor:
T. Sendlar

By his Attorney John O. Seifert

UNITED STATES PATENT OFFICE

THEODOR SENDLER, OF STETTIN, GERMANY

APPARATUS FOR DRYING CLOTHES, LAUNDRY, ETC.

Application filed February 24, 1930, Serial No. 430,556, and in Germany September 16, 1929.

The present invention relates to an apparatus for drying clothes, laundry, etc., more particularly towels and other articles of a like nature.

5 Laundry drying apparatus are already known, in which a plurality of drying bars are mounted in superimposed fashion on a board or the like by means of hinges, so that for the purpose of use these bars may be 10 swung out away from the board in any suitable inclined position. It has also been usual to make the bars fold back on to the board, so that when not in use the same assume a minimum amount of space.

15 The object of the present invention is to generally improve on drying apparatus of the kind referred to, and a principal feature of the invention consists in arranging the bars within a closed, box-like container, so 20 that the same, when not in use, are not visible and the whole apparatus possesses merely the appearance of a closed box or chest, which may be provided with suitable ornamentation on the exterior.

25 The drying bars are, according to the invention, so arranged in superimposed fashion that when the one bar is moved out of the normal position, this bar moves the remainder conjointly, thus greatly facilitating the 30 manipulation.

It is a further object of the invention to arrange the drying bars in such manner that when one of the drying bars, which is furnished with a handle, is moved out of the 35 box-like casing, this movement simultaneously causes the lid of the casing to be lifted, so that the casing is then open.

The apparatus according to the invention 40 may accordingly be moved into the position for use by one single manipulation.

The invention will now be described more fully with reference to the accompanying drawings, in which

45 Fig. 1 shows the drying apparatus in closed condition, viewed from the front.

Fig. 2 is a similar view of the drying apparatus with the lid open, and with the drying bars still folded back in the inoperative 50 position.

Fig. 3 is a perspective view of the apparatus in the position of use.

Fig. 4 shows on enlarged scale the connection of the single superimposed bars,

Fig. 5 being a cross-section through a drying bar according to the line V—V in Fig. 4.

In closed condition the drying apparatus forms a flat box or chest, which may be secured to the wall by means of eyelets, rings or the like *a*. The box consists of a rear board *b*, to the two side edges and the upper edge of which are secured projecting ledges or side portions *c*, *c*¹, *c*². To the side portion *c*¹ there is secured by means of hinges *d* the lid *e*. Against the inner side of the lid *e* there thrusts the one end of a spiral spring *f*, which is secured to the side portion *c*¹, and the other end of which thrusts against the board or panel *b*. The spring *f* is tensioned when the lid is closed, and upon the retraction thereof it will lift the lid into the position shown in Fig. 2. On the board or panel *b* there are provided on each side in the vicinity of the side portions *c* and *c*² two sockets *g*, these sockets being situated in suitable spacial relation one above the other and secured by means of screws or rivets. The two sockets on each side of the board *b* are connected by means of a shaft or rod *h*, and on each shaft or rod there are mounted a

75 number of, for example three, drying bars *i*, which are capable of freely rotating and are maintained at a suitable distance apart with the assistance of sleeves *k*. The drying bars *i*, at the ends at which they are mounted on the rod *h*, are constructed to form sockets *i*¹, and are made to be somewhat shorter than the distance between the two rods *h*. The bars *i* may be made of a suitable material such, for example, as wood, aluminium, plated iron or brass. Preferably the bars will be made of aluminium in order to render them as light as possible. The bars will also preferably be corrugated along the upper edge, and if made of aluminium will be furnished with the cross-section according to Fig. 5.

85 90 95 100 The sleeves *k* situated between each two bars have the object of holding the bars at a certain distance apart, and this distance

should be such that between two bars mounted on the one side of the apparatus a bar mounted on the opposite side of the board or panel *b* is capable of passing or resting without obstruction when all bars are folded back against the board, as shown in Fig. 2. The bars mounted at the one end of the board *b* are accordingly situated in staggered relation to the bars mounted at the opposite end of the board.

The lowermost bar *i* mounted on the left hand side of the board *b* possesses at its free end a grip *m*, which in the folded back position of the bars extends beyond the lower edge of the board *b*, so that the same projects out of the box when the apparatus is closed, as shown in Fig. 1.

The socket *i*¹ of the lowermost bar possesses a stud or abutment *n* (Fig. 4), which engages in an incision in the sleeve *k* situated above, so that when the bar *i* is moved about the rod or shaft *h*, the sleeve *k* participates in this rotary movement. The sleeve *k* possesses at its upper edge a stud or abutment *n*¹ engaging in an incision *o* in the lower edge of the socket of the second bar *i*. The incision *o* is of such size that when the sleeve *k* is rotated conjointly with the lowermost bar *i* the stud *n*¹ is at first compelled to perform an idle movement before it strikes against the end portion of the incision *o*. Only after a certain movement on the part of the sleeve *k* does the stud *n*¹ strike against the end portion of the incision, so that the second bar is not actuated until the lowermost bar has already moved to a certain extent. Consequently the two bars upon their movement about the rod or shaft *h* are disposed to a certain extent in staggered relation to each other.

On the socket *i*¹ of the second bar *i* there is also provided a stud *n*, which in turn engages in a corresponding incision in the sleeve above, accordingly moving the latter upon the movement of the bar *i*. The sleeve *k*¹ is connected with the topmost bar *i* in a manner similar to the connection of the second bar with the sleeve situated thereunder, so that when the lowermost bar *i* is swung away from the board *b* about the rod *h* the topmost bar is also moved, viz., at a slightly delayed period in relation to the movement of the second bar. By this method of connection all three bars may be moved simultaneously about the rod *h*; they may, however, be situated in staggered relation to each other, so that they are not essentially required to be superimposed to each other when, as shown in Fig. 3, they are moved out of the casing. In other words—although the three bars are moved conjointly their actuation is initiated successively, so that upon drawing out the lowermost bar the bars automatically assume a staggered adjustment.

The three drying bars *i* on the opposite end of the board may be mounted in similar man-

ner, so that when the lowermost rod *i* of those mounted in the vicinity of the end portion *c*² is moved away from the board *b* the two remaining rods are also moved.

On the lowermost drying bar *i* mounted on the left there may be provided a pin *p* which, when the drying bars are in the position of rest, engages behind the lowermost rod *i* mounted on the right.

On the lid *e* there is provided on the right hand side edge a small plate *q*, which projects to a slight extent beyond the side edges of the lid. In the closed position of the lid the edge of the small plate *q* thrusts against a spring *r*, which is mounted on the side portion *c*² and requires to be of such strength that the same is capable of holding the lid *e* in the closed state.

If the drying apparatus is in the closed position, i. e., according to Fig. 1, the grip *m* projects out of the box or chest, which is open only at the lower edge. If the grip *m* is subjected to a pulling action, the lowermost drying bar *i* presses against the lid *e*, whereby the force of the spring *r* is overcome and the plate *q* forced away from the spring. The lid *e* under the action of the spring *f* will then be moved into the open position shown in Figs. 2 and 3. By the withdrawal of the grip *m* the lowermost bar *i* is rotated about the hinge rod *h* and, by reason of the operating means *i*¹, *n*, *k*, *n*¹, *o*, conjointly moves the second bar, which in turn also moves the third bar, so that all three bars on the one side of the apparatus will be swung out into the position for use as shown in Fig. 3. At the same time upon the movement of the lowermost bar *i* the projection *p* will conjointly move the lowermost bar on the right hand side, which in turn actuates those situated above. By the one actuation of the grip *m* all drying bars will accordingly be moved out into position at the same time as the opening of the lid *e*.

It is of course quite understood that no restriction is made to the specific form of embodiment shown, and that various modifications are possible within the meaning of the above and the annexed claims without departing from the spirit of the invention.

Thus, for example, the operating means *n*, *n*¹ by which the bars *i* on each side of the apparatus are connected together may also be constructed in other form, and alternatively the drying apparatus might be such that drying bars are provided only on the one side of the same.

Neither is the invention restricted to the use of merely three bars on each side, and it is quite possible to provide merely two or also any greater number.

Owing to the fact that the rods *i* are corrugated along the upper edge the articles placed over the same for drying purposes will contact therewith only at certain single points, so that circulation of the air is quite possi-

ble, even along the bars. Owing to this circulation of the air it is accordingly quite possible for the laundry to dry at all points with equal rapidity, including those sections by which the same is suspended on the bars.

What I claim as new and desire to secure by Letters Patent is:

1. In a laundry drying apparatus, a casing having an opening in the front, a pair of vertical shafts one fixed adjacent each end of and within the casing, a plurality of superimposed bars pivotally mounted on said shafts to be swung in a substantially horizontal plane outward through the opening in the casing and into the casing and connected to each other so that upon actuation of one bar all of the remaining bars are conjointly moved therewith, a lid hingedly mounted on the casing to close the opening, means to releasably retain the lid in closed position to enclose the bars in the inoperative positions thereof, the lid being adapted to be automatically released upon the outward actuation of the bars, and a spring to move the lid to open position when released.

2. In a form of embodiment of a drying apparatus for laundry, a plurality of drying bars divided into two sets of superimposed bars, the bars of the one set being arranged in staggered relation to the bars of the other set, and each set pivotally mounted on a vertical shaft, means for causing conjoint movement of the said bars, a box-like casing having an opening in the front in which the shafts are fixed and adapted to enclose the said bars, a folding lid to the said casing rendering the said bars invisible when the apparatus is not in use, and means for causing the lid to open automatically conjointly with the actuation of the said bars.

3. In a form of embodiment of a drying apparatus for laundry, a plurality of drying bars divided into two sets of superimposed bars, the bars of the one set being arranged in staggered relation to the bars of the other set, a vertical shaft upon which the bars of each set are pivotally mounted, distance sleeves mounted on the said shaft between the single bars, studs on the said bars adapted to engage with play in incisions in the said sleeves, a box-like casing having an opening in the front in which the shafts are fixed and adapted to enclose the said bars and operating means, a folding lid to the said casing rendering the said bars invisible when the apparatus is not in use, and means for causing the said lid to open automatically conjointly with the actuation of the said bars.

4. In a form of embodiment of a drying apparatus for laundry, a plurality of drying bars divided into two sets of superimposed bars, the bars of the one set being arranged in staggered relation to the bars of the other set so as to enable the bars of the one set to pass freely in interengaging fashion be-

tween the bars of the other set, a vertical shaft upon which the bars of each set are pivotally mounted, distance sleeves mounted on the said shaft between the single bars ensuring the necessary spacing, studs on the said bars adapted to engage with play in incisions in the said sleeves, a grip on the free end of the lowermost bar, a box-like casing having an opening in the front in which the shafts are fixed and adapted to enclose the said bars and the operating means therefor, a folding lid to the said casing rendering the said bars invisible when the apparatus is not in use, and means for causing the said lid to open automatically conjointly with the actuation of the said bars upon manipulation of the said grip.

5. In a form of embodiment of a drying apparatus for laundry, a plurality of drying bars divided into two sets of superimposed bars, the bars of the one set being arranged in staggered relation to the bars of the other set, a vertical shaft upon which the bars of each set are pivotally mounted, distance sleeves mounted on the said shafts between the single bars, means for causing conjoint movement of the bars of each set upon actuation of the lowermost bar, a pin on the free end of the lowermost bar of the one set engaging behind the lowermost but more elevated bar of the other set, a grip on the free end of the lowermost bar, a box-like casing having an opening in the front in which the shafts are fixed and adapted to enclose the said bars and the operating means therefor, a folding lid to the said casing rendering the said bars invisible when the apparatus is not in use, and means for causing the said lid to open automatically conjointly with the actuation of the said bars upon manipulation of the said grip.

6. In a form of embodiment of a drying apparatus for laundry, a plurality of drying bars divided into two sets of superimposed bars and corrugated along the upper edge, the bars of the one set being arranged in staggered relation to the bars of the other set, a vertical shaft upon which the bars of each set are pivotally mounted, distance sleeves mounted on the said shafts between the single bars, means for causing conjoint movement of all the bars of both sets upon actuation of the lowermost bar, a box-like casing having an opening in the front in which the shafts are fixed and adapted to enclose the said bars and the operating means therefor, a folding lid to the said casing rendering the said bars invisible when the apparatus is not in use, a spring mounted on the said casing and holding the said lid in the closed condition, a plate mounted on the said lid thrusting against the said spring, and a second spring adapted to lift the said lid conjointly with the actuation of the said bars.

7. In a form of embodiment of a drying apparatus for laundry, a plurality of drying bars divided into two sets of superimposed bars and corrugated along the upper edge, the bars of the one set being arranged in staggered relation to the bars of the other set so as to enable the bars of the one set to pass freely in interengaging fashion between the bars of the other set, a vertical shaft upon which the bars of each set are pivotally mounted, distance sleeves mounted on the said shafts between the single bars, studs on the said bars adapted to engage with play in incisions in the above-situated sleeves, a pin on the free end of the lowermost bar of the one set engaging behind the lowermost but more elevated bar of the other set, a grip on the free end of the lowermost bar, a box-like casing having an opening in the front in which the shafts are fixed and adapted to enclose the said bars and the operating means therefor, a folding lid to the said casing rendering the said bars invisible when the apparatus is not in use, a spring mounted on the said casing and holding the said lid in the closed condition, a plate mounted on the said lid and thrusting against the said spring, and a second spring adapted to lift the said lid conjointly with the actuation of the said bars by manipulation of the said grip, the arrangement being such that the said lid is lifted and the bars of each set moved out of the said casing and caused to assume staggered positions upon one single manipulation of the said grip.

In testimony whereof I have affixed my signature.

THEODOR SENDLER.
